UNITED STATES PATENT OFFICE.

GEORGE F. CONNER, OF PORT HURON, MICHIGAN.

DESIGN FOR A WRENCH.

SPECIFICATION forming part of Design No. 32,401, dated March 27, 1900.

Application filed March 1, 1900. Serial No. 7,022. Term of patent 14 years.

To all whom it may concern.

Be it known that I, GEORGE F. CONNER, a citizen of the United States, residing at Port Huron, in the county of St. Clair and State of Michigan, have invented and produced a new and original Design for Wrenches, of which the following is a specification, reference being had to the accompanying drawings, forming a part thereof.

10 This invention relates to an original design for wrenches; and it is embodied in the form and configuration shown and hereinafter described.

In the drawings, Figure 1 illustrates the invention in side elevation. Fig. 2 is an edge view.

15 A designates a straight body portion having at one end an enlarged head B, formed with curved upper and lower portions lying 20 above and below the body portion. The head is carried outward and slightly curved downward and has an incision or cavity formed in its outer edge, with a curved wall b terminating in a right-angle shoulder b'. The outer 25 edge of the shoulder constitutes a terminal of

a wall of the outer edge of the opposite part of the head. The opposite end of the body carries a head C of a shape substantially that of the opposite head, but smaller in proportion, having a similarly-shaped long and short 30 jaw and peculiarly-shaped throat between same. The transverse width of the heads is greater than the width of the body portion, as shown in Fig. 2.

The essential feature of the design is the 35 peculiar shape of the heads, the long and short jaws, and the curved connecting-throat, and the connecting body portion shown and described.

Having thus described my invention, what 40 I claim as new, and desire to secure by Letters Patent, is—

The design for a wrench, substantially as shown and described.

In testimony whereof I have affixed my sig- 45 nature in presence of two witnesses.

GEORGE F. CONNER.
